UNITED STATES PATENT OFFICE.

LUDWIG LÖWY, OF DUSSELDORF, GERMANY, ASSIGNOR TO SCHLOEMANN AKTIEN-
GESELLSCHAFT, OF DUSSELDORF, GERMANY, A CORPORATION OF GERMANY.

MANDREL-UPSETTING PRESS.

Application filed March 25, 1926, Serial No. 97,252, and in Germany April 1, 1926.

My invention relates to mandrel upsetting presses and has for its purpose to provide means for making the construction and operation of such presses more economical at the same time increasing the output.

In the rolling of tubes by the so-called Perins process the mandrels used therein, due to the pressure of the rolls, have their diameter reduced, while in axial direction they are lengthened, the mandrels also losing their cylindrical shape. To enable these mandrels to be used over again, their original diameter must be restored, and to this end they are upset in axial direction in hydraulic presses. Heretofore, the mandrels have been upset in cylindrical chill moulds made of two parts, which means, of course, that for each diameter a special mould is required. This in turn means a considerable outlay for a large number of moulds, not to mention the time required for exchanging the molds. The present invention has for its object to eliminate these great drawbacks, and I accomplish this by providing a single mould or matrix in which are provided three, four or more concentric arch-shaped members, which are radially adjustable. In this manner, a single mould or matrix can be employed for any desired number of mandrels having various diameters. Moreover, every mandrel can be exactly centrally positioned within the mould or matrix, so that the press-plunger is subjected only to central strains.

For a better understanding of my invention, I refer to the following detailed description with reference to the appended drawing, in which I have illustrated one embodiment of my invention by way of example, and in which Fig. 1 is a side elevation of the closed mould, the means for varying the position of the arch-shaped members being provided on the outside, the figure also showing the projecting ends of the mandrel; Fig. 2 is a cross-section of the divided closed mould, the arch-shaped members being shown drawn apart from each other for the upsetting of a mandrel of very large diameter; Fig. 3 is a similar cross-section as Fig. 2 showing the arch-shaped members pushed toward each other for the upsetting of a mandrel of medium diameter.

a is the divided casing of the mould, which is closed by hydraulic cylinders (not shown). Within the casing *a* are mounted four arch-shaped members *b*, which may be simul-

taneously adjusted relative to each other by a manually operated wheel (not shown) through sprocket-wheels *c*, worms *d*, worm-wheels *e* and screw-spindles *f*. By this mechanism, the four arch-shaped members *b* can be uniformly moved from the center of the casing, the said member constituting the cylindrical mould for the mandrels *g* to be subjected to the upsetting operation. The arch-shaped members are shaped in such a way that after the upsetting operation, they contact with the mandrel each along two lines. As experience has shown, these eight contact lines of the arch-shaped members *b* with the mandrel *g* suffice, so that the mandrel will be perfectly round.

The operation is as follows:

After the said arch-shaped members *b*, by means of the sprocket-wheels *c*, worms *d*, worm-wheels *e* and screw-spindles *f* have been adjusted to the correct diameter of the mandrel, the upper half of the casing *a* is lifted, and the hot mandrel *g* to be upset is placed into the lower half of the casing so that the one end bears against the abutment *h* (Fig. 1). Now, by the application of hydraulic pressure, the upper half of the casing is pressed onto the lower half, whereupon the press-plunger *i* (Fig. 1) is moved toward the left in Fig. 1 in the direction of the arrow, upsetting the mandrel in axial direction until its surface everywhere bears on the contact lines of the previously positioned arch-shaped members *b*. After the upsetting operation has been completed, the press-plunger *i* is withdrawn, the upper half of casing *a* is lifted, and the mandrel is removed from the lower half of the casing, and a fresh mandrel can now be placed therein.

While I have thus described my invention in detail, I do not, of course, limit myself to the details of construction as shown, since various modifications will easily suggest themselves to those skilled in the art within the scope of my invention.

I claim:

1. In a mandrel upsetting press, the combination with a casing, of a plurality of movable arcuate members concentrically positioned in said casing, means for adjusting said members relative to each other, means for upsetting a mandrel positioned within said arcuate members, and mechanism for rigidly maintaining said movable arcuate members in position during said upsetting.

2. In a mandrel upsetting press, the combination with a casing, of a plurality of adjustable arcuate members concentrically positioned in said casing and adapted to bear against the mandrel, means for uniformly moving said members toward and away from the central longitudinal axis of said casing, means for upsetting a mandrel positioned within said arcuate members, and mechanism for rigidly maintaining said movable arcuate members in position during said upsetting.

3. In a mandrel upsetting press, the combination with a casing, of a plurality of adjustable arcuate members concentrically positioned in said casing and adapted to each contact with the mandrel along two lines, means for simultaneously moving said members toward and away from the central longitudinal axis of said casing, means for upsetting a mandrel positioned within said arcuate members, and mechanism for rigidly maintaining said movable arcuate members in position during said upsetting.

4. In a mandrel upsetting press, the combination with a casing comprising a lower and upper half, of a plurality of adjustable arcuate members concentrically positioned in said casing and adapted to make contact with

the mandrel along two or more lines, manually operated mechanism for radially and uniformly adjusting said members relative to the central longitudinal axis of said casing, means for upsetting a mandrel positioned within said arcuate members, and mechanism for rigidly maintaining said movable arcuate members in position during said upsetting.

5. In a mandrel upsetting press, the combination with a casing, of four movable arcuate members concentrically disposed in said casing and adapted to make contact with the mandrel with their inner ends, means for uniformly adjusting said members relative to the central longitudinal axis of said casing, said means comprising screw-spindles cooperating with said members and carrying worm-wheels, worms meshing with said worm-wheels, spindles carrying said worms, and a manually operated wheel for rotating said spindle, means for upsetting a mandrel positioned within said arcuate members, and mechanism for rigidly maintaining said movable arcuate members in position during said upsetting.

In testimony whereof I affix my signature.
LUDWIG LÖWY
